UNITED STATES PATENT OFFICE.

LEE ROY B. HOUSE, OF HERRIN, ILLINOIS.

TEETH.

Application filed January 27, 1925. Serial No. 5,122.

This invention has as one of its objects, the provision of a novel means whereby a porcelain denture and its backing may be assembled without resorting to solder, the teeth disclosed in this application being interchangeable, so that any one tooth may be replaced by another, upon occasion. The invention aims to provide novel means whereby an artificial tooth may be secured to the backing which

10 supports it.

Although preferred forms have been depicted, it will be understood that a dentist, working within the scope of what is claimed, may make such alterations as the skill of his calling may suggest, without departing from

15 the spirit of the invention.

In the accompanying drawings:—

Figure 1 shows in elevation, a tooth embodying the invention; Figure 2 is a view 20 wherein the tooth of Figure 1 is disclosed at right angles to the showing of that figure; Figure 3 is an elevation of the tooth on the lingual side; Figure 4 is a longitudinal section; Figure 5 is a cross section on the line 25 5—5 of Figure 2; Figure 6 is a perspective view showing the backing.

In the form shown in Figures 1 to 6, the invention is embodied in a porcelain anterior tooth comprising a body 1, the lingual surface 30 of which is marked by the numeral 2, the same being bounded at one end by a shoulder 3 which is continued as shown at 4 along the sides of the tooth to the incisal edge thereof. A bore 5 extends into the body 1 from the 35 lingual surface 2, longitudinally of the tooth and in a direction parallel to the root of the tooth. The backing 6, made of gold or the

like, conforms to the surface 2 of the tooth and includes a main portion 7 and wings 8, the backing cooperating with the shoulders 3 40 and 4. The main portion of the backing 6 carries a post 9 held by cement 10 in the bore 5, the main portion 7 of the backing 6 being extended, as at 11, upon the incisal edge of the tooth.

Having thus described the invention, what is claimed is:—

A denture embodying a tooth supplied with a shoulder and with an incisal portion, the shoulder terminating at its ends at the incisal portion of the tooth, the tooth being supplied with a surface which is inclined and bounded by the shoulder on three of its edges, a backing cooperating with the aforesaid inclined surface of the tooth and abutting against the shoulder, the backing being of substantially a common thickness throughout its entire extent, and being fashioned from thin, plate-like material, the backing having an extension which is over-lapped on the incisal portion of the tooth, the incisal portion of the tooth being disposed approximately parallel to the intermediate portion of the shoulder, the tooth having a bore, and a post cemented in the bore, the bore and the post extending in the general direction of the length of the tooth, the post being secured to the backing and being located at the extreme forward edge of the backing, directly in the rear of the extension.

In testimony that I claim the foregoing as my own, I have hereto affixed my signature.

LEE ROY B. HOUSE.
